GAME BOARD

Edwin I. Scharf, Floyd Knobs, Ind., assignor of one-third each to Chester B. Stem and Historic New Albany, Inc., both of New Albany, Ind., and both corporations of Indiana

Filed Jan. 2, 1968, Ser. No. 10,022

Term of patent 14 years

(Cl. (D34—5)

The figure is a top view of my game board, showing my new design. The board is of conventional thickness.

I claim:

The ornamental design for a game board, as shown and described.
